UNITED STATES PATENT OFFICE.

DANIEL W. HAYDEN, OF PROVIDENCE, RHODE ISLAND.

STOP MECHANISM FOR DRAWING-FRAMES.

SPECIFICATION forming part of Letters Patent No. 227,002, dated April 27, 1880.

Application filed May 19, 1879.

To all whom it may concern:

Be it known that I, DANIEL W. HAYDEN, of the city and county of Providence, State of Rhode Island, have invented a new and useful Improvement in Stop Mechanisms for Drawing-Frames; and I hereby declare that the following is a full, clear, and exact description of the same, reference being had to the accompanying drawings, forming part of this specification.

This invention has reference to improvements in the construction of stop mechanism applicable to drawing-frames and cotton-sliver eveners or railway-heads; and it consists in the peculiar construction of the parts herein-after claimed for detaching the driving mechanism both when the sliver breaks and the trumpet becomes choked.

Figure 1 is a view of my improved stop mechanism shown in connection with the detaching mechanism when the sliver passing through the trumpet is of the required size. Fig. 2 shows the position of the various parts when excessive friction is produced on the trumpet by a heavy sliver passing through the same, or when the trumpet is choked, in solid lines, and in broken lines in the position occupied when the sliver is broken.

In the drawings, *a a* represent the drawing-rolls; *b*, the trumpet secured to the arm *b'* and hinged on the fulcrum *c*. A long lever, *d*, is connected by an adjustable connection to the horizontal arm of the arm *b'*, and the lever *d* is provided with an adjustable weight, *e*, the end of the lever *d* being provided with a hook. Connected with the lever *d* by a jointed link-connection, *f*, is the stop-pawl *g*, hinged at the bottom and provided with an adjustable balance-weight, *g'*, sliding on a horizontal pin.

h is an oscillating arm mounted on a rocking shaft, and provided with a stud on which the V-shaped riding pawl connected with the eccentric *h* rests, and by which it is oscillated so long as the arm *h* is free to oscillate. The arm *h* is also provided with the hook or projection *h'*, with which the hook on the lever *d* engages when the sliver breaks, and by which the oscillation of the arm *h* is prevented. 50 Another curved projection, *h''*, oscillates close

to the stop *g*, and when an extra strain is exerted on the trumpet, sufficient to raise the additional weight *g'*, the stop *g* will interfere with the projection *h''* and prevent the arm *h* from oscillating.

When, therefore, the sliver passing through the trumpet becomes too light to balance by its friction the weight *e*, the oscillation of the arm *h* will be arrested, and when the trumpet chokes the same result will follow.

When the arm *h* is prevented from oscillating freely, the V-shaped riding pawl will be pushed over the pin and will rise, and in its turn will raise the slide *l*, through a slot in the upper part of which the riding lever *i* passes.

m is a roll inserted in the slot at the upper end of the slide *l* to avoid friction. The lower end of the slide *l* is connected with and operates the hinged arm *n*, the other end of which is arranged to disengage the shipper mechanism.

The stop mechanism may be adjusted by moving the weights *e* and *g'*. It is very sensitive in its operation, and can be used on a railway-head by passing the cotton sliver first through the ordinary evener-trumpet, by means of which the speed of the drawing-rolls is regulated, then through the delivery-rolls, over and around the same, through the supplementary trumpet *b*, and again through the delivery-rolls to the cans, the first trumpet controlling the speed-regulating mechanism, and the second trumpet the stop mechanism.

I do not wish to confine myself to any particular kind of belt-shipper mechanism, this forming no part of this invention; but for the purpose of illustration I would refer for a description of a belt-shipper mechanism to my application for improvements in cotton-sliver eveners, filed simultaneously with this present application.

Having thus described my invention, I claim as new and desire to secure by Letters Patent—

1. The combination, with the trumpet *b* and the lever *b'*, of the arm *h*, having the stops, as described, and the lever *d*, arranged, as described, to interfere with the oscillation of the arm *h*, and the stop *g*, arranged to interfere

with the projection h' , and provided with the adjustable weight g' , the lever d and stop g being connected by a hinged link, substantially as and for the purpose set forth.

5 2. The combination, with the trumpet, its supporting-lever, and the lever d , of the hinged stop g , provided with the auxiliary weight g' , the hinged link or connection f , the arm h , and

mechanism for oscillating said arm, all arranged to operate substantially as and for the purpose set forth.

D. W. HAYDEN.
